UNITED STATES PATENT OFFICE.

ERNST SUSSMANN-HELLBORN AND WILHELM HORNAUER, OF MUNICH,
GERMANY.

ELECTRIC RAILWAY.

SPECIFICATION forming part of Letters Patent No. 663,398, dated December 4, 1900.

Application filed October 11, 1900. Serial No. 32,770. (No model.)

To all whom it may concern:

Be it known that we, ERNST SUSSMANN-HELLBORN and WILHELM HORNAUER, citizens of Germany, residing at Munich, Germany, have invented certain new and useful Improvements in Electric Railways; and we do hereby declare the following to be a full, clear, and exact description of the invention, such as will enable others skilled in the art to 10 to which it appertains to make and use the same.

The object of the present invention is to feed the electric current to motor-cars by means of induction instead of by means of the various contact devices hitherto generally employed. The devices hitherto employed for feeding electricity to cars by means of induction are too complicated to be of practical importance.

The device forming the object of the present invention is of very simple construction and is easily adapted to the various systems in vogue. The invention is applicable both to single-phase (alternating) and to multiple-phase currents.

25 The essential feature of the application consists in the enlarged or extended employment of a divided transformer the primary windings of which are arranged in the ground or underground, while the secondary windings 30 are mounted on the car and move with the same. The primary windings must consequently be continuous, so as to enable the car elements to always receive the current by induction produced by the primary elements 35 and to feed the same to the electric motors on the car.

In order to render the present specification easily intelligible, reference is had to the accompanying drawings, in which similar letters of reference denote similar parts throughout the several views.

Figure 1 is a diagram showing the arrangement of the elements in the tracks, and Fig. 2 a similar diagram showing the arrangement 45 of the car elements or windings. Fig. 3 shows a modified arrangement for primary elements, and Fig. 4 a modified arrangement of the primary elements for multiple-phase currents. Fig. 5 is a side elevation, and Fig. 6 a plan, 50 showing the arrangement of the conductors.

As will be seen from Fig. 1, the primary windings or elements *a* are arranged in the ground, electricity being fed to the same by means of high-tension conductors in suitable manner. The spools consist of the U-shaped 55 iron cores *c*, having the shoes *b*, the upper surfaces of which are either flush with the level of the street or arranged slightly below the same. The primary elements are mounted on the vertical shanks of the U-shaped cores. 60 These elements may be worked at any suitable high tension, according to circumstances.

The arrangement of the secondary elements—*i.e.*, that part of the divided transformers which is on the car—is similar to that 65 of the primary ones, as will be seen from Fig. 2 and as indicated by *f*. In order to attain a better effect, on the one hand, and to be able to utilize the whole length of the car for the induction without having to increase the number of the second windings *f*, the corresponding poles of the car elements, which are all arranged on one side of the car, (as will be seen from Fig. 2, which shows the adaptation 70 of the invention for single-phase alternating currents,) are constructed as continuous laminated iron straps or binders *g*, extending throughout the length of the car. The shape and distance apart of the connecting girders or bars are designed to enable the 75 greatest possible absorption of the field-lines without, however, seriously impairing the effect by radiation in the case of three or more parallel girders, as is necessary for multiple-phase current. According to the first arrangement the distance apart of the primary elements *a* of the transformers is calculated 80 so as to allow the secondary winding *f* to reach the next-lying primary element before it has left the previous one. Thus the distance apart of the primary elements must be 85 determined by the length of the car. In order, however, to increase the effect and to enable the arrangement of the elements still farther apart, the shoes of all the primary elements are combined at each side *h* and *i* to form a continuous iron bar or girder, as 90 shown in Figs. 3 and 4, which should be constructed according to the particular class of the core of the transformer. Owing to the 95 100

good magnetic conducting capability of iron the primary coils a may be arranged as far apart as is compatible with the variations of the tension at the poles of the motor. Since 5 these tension variations are mainly due to a reduction of the effective field-lines, it will be readily understood that, having due regard to the slight magnetic resistance of the iron, it will be possible to materially increase the 10 distance apart of the primary elements of the transformers in the direction of the track before any substantial alteration in the amount of the field-lines will take place.

By reducing the number of the primary elements and by connecting up the shoes of the 15 same at each side the following advantage is attained: Assuming that for the moment no car is standing over any one primary element, the whole space lying between two elements 20 and between the two compound girders or binders is presented as transmitting space for the field-lines originating in such element. Thus a considerable reduction of the magnetic resistance of the air is attained—*i. e.*, the 25 work of the primary elements when no car is running over them will be considerably reduced, which is of great importance in connection with lines on which the cars do not run very often. Apart from this the self-induction 30 of the primary elements of the transformers may be increased to any desired extent by enlarging the iron core, which enlargement would but very slightly influence the prime cost of the plant.

35 Figs. 1 to 3 relate to the application of the invention for alternating currents. For multiple-phase currents three girders are employed in place of the two h i , both underground and on the car, and the presence of 40 three parallel girders still further reduces the amount of work when no car is running. The arrangement of the primary elements for multiple-phase current is illustrated in Fig. 4. In connection with this class of current the insensibility of the motor as regards the variations of tension is a great advantage and admits a still further increase in the distance 45 apart of the primary elements on each girder.

On the car two or more secondary elements 50 f f are arranged in series in order to compensate for the difference of tension due to the reduction of the field-lines in the various secondary spools by their coöperation. This offers a further possibility of increasing the 55 distance apart of the primary elements of the transformer.

If the track has a number of curves and the car has to be provided with bogies, the girders g must be separately mounted on each 60 part of the car-frame, and they may be magnetically connected one with the other.

It should be mentioned here that the high tension at which the primary elements may 65 eventually be charged involves no danger for the general traffic. In connection with tracks for electric railways running through public streets only the girders h i approach the sur-

face of the street, while the well-insulated primary elements, of high tension, as also the main conductors, lie at a considerable depth 70 below the level of the street. If necessary, still greater safety might be attained by connecting up all the girders electrically and by locating the neutral point on the ground.

The complete electrical connections are 75 illustrated in Figs. 5 and 6. As will be seen from these figures, the conductors m extend from the source of electricity l along the track, and the primary elements a of the transformer are connected up to the same by branch conductors n in multiple arc or else in series, as shown in Fig. 6. The zero-point of the winding of the transformer is in connection with the central girder o , while the outside girders o are connected with the central girder by 85 conductors p in order to prevent danger in the case of ineffective insulation. In order as far as possible to reduce the work of the primary elements when no cars are running, a condenser v is arranged in parallel connection at suitable intervals. The transmission of energy to the car takes place in the following manner: The primary elements of the 90 transformers are excited by the high-tension current coming from the source of electricity, 95 by which means strong magnetism will be induced in the compound girders o extending along the track. The induction is transmitted to the girders or bars g of the car, and thus alternating current of low tension is generated in the secondary elements or windings 100 and serves to drive the car.

We claim as our invention—

1. Means for feeding electricity to motor-cars by induction comprising a divided transformer having the primary elements embedded in the ground and the secondary elements or windings on the car, the iron cores of the primary and also of the secondary elements being each continuously magnetically connected up 105 among themselves, parallel to the direction of the rails by means of a plurality of parallelly-located compound iron binders between the rails and on the car in the manner and for the purpose substantially as described. 115

2. In a device for feeding electricity to motor-cars by induction comprising the primary elements located in the ground and secondary elements located on the car, the combination of at least two secondary elements 120 mounted on each iron binder of the car said elements being connected up in series for the purpose substantially as described.

3. The combination in an electric railway, of transformers having the primary elements 125 distributed along the line and the secondary elements located on the car, said primary elements having magnetic bars extending along the line and connecting the extremities of like polarity, said secondary elements on the 130 car also having magnetic bars connecting the extremities of like polarity, said bars on the car being arranged to travel in proximity to the said bars extending along the line, and

an electric motor on the car connected with said secondary elements, said latter elements being connected up in series with said motor.

4. The combination in an electric railway, 5 of transformers having the primary elements distributed along the line and the secondary coils located on the car, the said primary elements of the transformers having their unlike extremities connected by a magnetic bar, 10 and magnetic bars extending along the line and connecting the other ends of said primary elements, each of said latter bars connecting extremities of like polarity of the said primary elements, the said secondary elements 15 of the transformers having their unlike extremities connected by a magnetic bar, and longitudinally-arranged magnetic bars connecting the other ends of said secondary elements, each of said latter bars connecting 20 extremities of like polarity of the secondary elements, said longitudinal bars on the car being arranged to travel in proximity to said bars extending along the line, and an electric motor on the car connected with said secondary elements of the car.

5. The combination in an electric railway, of transformers having the primary coils distributed along the line and the secondary elements located on the car, the said primary 30 elements of the transformers having their unlike extremities connected by a magnetic bar, and magnetic bars extending along the line and connecting the other ends of said primary elements, each of said latter bars connecting 35 extremities of like polarity of the said primary elements, the said secondary elements of the transformers having their unlike extremities connected by a magnetic bar, and longitudinally-arranged magnetic bars connecting the 40 other ends of said secondary elements, each of said latter bars connecting extremities of like polarity of the secondary elements, said longitudinal bars on the car being arranged to travel in proximity to said bars extending 45 along the line, and an electric motor on the car connected with said secondary elements of the car, said latter elements being connected up in series with said motor.

6. The combination in an electric railway, 50 of polyphase transformers having the primary elements distributed along the line and the secondary elements located on the car, the said primary elements of the transformers having their unlike extremities connected by a magnetic bar, and magnetic bars extending 55 along the line and connecting the other ends

of said primary elements, each of said latter bars connecting extremities of like polarity of the said primary elements, the said secondary elements of the transformers having 60 their unlike extremities connected by a magnetic bar, and longitudinally-arranged magnetic bars connecting the other ends of said secondary elements, each of said latter bars connecting extremities of like polarity of the 65 secondary elements, said longitudinal bars on the car being arranged to travel in proximity to said bars extending along the line, and an electric motor on the car connected with said secondary elements of the car. 70

7. The combination in an electric railway, of polyphase transformers having the primary elements distributed along the line and the secondary elements located on the car, the said primary elements of the transformers having 75 their unlike extremities connected by a magnetic bar, and magnetic bars extending along the line and connecting the other ends of said primary elements, each of said latter bars connecting extremities of like polarity 80 of the said primary elements, the said secondary elements of the transformers having their unlike extremities connected by a magnetic bar, and longitudinally-arranged magnetic bars connecting the other ends of said 85 secondary elements, each of said latter bars connecting extremities of like polarity of the secondary elements, said longitudinal bars on the car being arranged to travel in proximity to said bars extending along the line, and an 90 electric motor on the car connected with said secondary elements of the car, said latter elements being connected up in series.

8. The combination in an electric railway, of polyphase transformers having the primary 95 elements distributed along the line and secondary elements on the car, said primary elements having magnetic bars extending along the line and connecting the extremities of like polarity, and means for electrically connecting 100 said magnetic bars with the neutral point of said primary elements.
